UNITED STATES PATENT OFFICE

146,768

DESIGN FOR A SHOE

John Henkel, Baltimore, Md., assignor to Dixon-Bartlett Company, a corporation of West Virginia

Application August 9, 1945, Serial No. 121,340

Term of patent 7 years

(Cl. D7—7)

To all whom it may concern:

Be it known that I, John Henkel, a citizen of the United States, residing in Baltimore city, in the State of Maryland, have invented a new, original, and ornamental Design for a Shoe, of which the following is a specification, reference being had to the accompanying drawing, forming part thereof, in which:

Figure 1 is a left side elevation of a shoe showing my new design.

Figure 2 is a left side front perspective view of the same.

Figure 3 is a right side perspective view of the same.

My design for a shoe of the step-in type is characterized by the arrangement of all the parts in a manner specifically as illustrated.

I claim:

The ornamental design for a shoe, substantially as shown and described.

JOHN HENKEL
